[57] CLAIM

The ornamental design for a case for a portable modem, as shown and described.

DESCRIPTION

FIG. 1 is a front, top, and left side perspective view of a case for a portable modem showing our new design; FIG. 2 is a front elevational view;

FIG. 3 is a rear elevational view;

FIG. 4 is a top plan view;

FIG. 5 is a bottom plan view;

FIG. 6 is a right side elevational view;

FIG. 7 is a left side elevational view;

FIG. 8 is a front, top, and left side perspective view of a second embodiment of that shown in FIG. 1;

FIG. 9 is a front elevational view;

FIG. 10 is a rear elevational view;

FIG. 11 is a top plan view;

FIG. 12 is a bottom plan view;

FIG. 13 is a right side elevational view; and,

FIG. 14 is a left side elevational view thereof.

The connecting cord in FIGS. 1 and 4-7 has been shown broken away to indicate indeterminate length. The broken line showings in FIGS. 8-14 are for illustrative purpose only and form no part of the claimed design.
